CLAIM

The ornamental design for basket for fryer, as shown and described.

DESCRIPTION

1. Basket for fryer

1.1 is a perspective view showing the basket for fryer of my design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

The portions of the basket for fryer shown in broken lines form no part of the claimed design.

1 Claim, 5 Drawing Sheets(56)
